HAIR-SETTING AND HAIR-TRIMMING
APPLIANCE

Joy H. Richmond, Beverly Hills, Calif.

Application June 5, 1951, Serial No. 229,923

2 Claims. (Cl. 132—45)

1

This invention relates to hair-setting devices, and more particularly to an improved appliance for obtaining a "page boy" coiffure.

A main object of the invention is to provide a novel and improved hair-setting appliance for obtaining a "page boy" effect, said appliance being simple in construction, being easy to use, and involving only a few parts.

A further object of the invention is to provide an improved hair-setting apparatus constructed to provide an easy method of obtaining a "page boy" style of coiffure, the appliance being inexpensive to manufacture, being readily adjustable in accordance with the contour and size of the user's head, and enabling the user to obtain the desired hair set with a minimum amount of effort.

Further objects and advantages of the invention will become apparent from the following description and claims, and from the accompanying drawings, wherein:

Figure 1 is a diagrammatic pictorial view showing an improved hair-setting appliance according to the present invention mounted in operative position on a person's head;

Figure 2 is a perspective view of the hair-setting appliance employed in Figure 1;

Figure 3 is a top plan view of the appliance of Figures 1 and 2;

Figure 4 is an enlarged cross-sectional detail view taken on the line 4—4 of Figure 3;

Figure 5 is an elevational view of the appliance in open position.

Referring to the drawings, the hair-setting appliance is designated generally at 11, and comprises a relatively thick, generally U-shaped bar member 12 which may be rounded or oval in cross-section, as for example, circular in cross-section, as shown in Figure 4, and which is formed along its length on its outwardly facing surface with a groove 13 adapted to receive the points of scissors when the device is employed for hair trimming.

Designated at 14 and 15 are respective rectangular plate members which are respectively pivotally secured adjacent corner portions thereof to the ends of the bar member 12, as shown at 16 and 17. The bar member 12 is formed of semi-rigid material, such as plastic or the like, the rigidity thereof being enhanced due to its substantial thickness. Designated at 18 is a relatively thin, auxiliary, U-shaped bar member pivotally secured at its ends to the corner portions of the plate members 14 and 15, as shown at 19 and 20, the member 18 being substantially

2

similar in shape and size to the relatively thick U-shaped member 12, although not being necessarily identical in shape and size thereto. The relatively thin U-shaped member 18 may be of plastic rod material of any suitable, semi-rigid type.

Designated at 21 is a strap member secured at one end thereof to the plate member 14, as shown at 22. The strap member 21 is formed at its opposite end portion with a plurality of rectangular apertures 23 spaced longitudinally along the strap member, said apertures 23 being adapted to be selectively engaged with a rectangular lug 24 projecting from the plate member 15, as shown in Figure 5. The strap member 21 is formed of plastic material or other suitable, relatively flexible strap material.

In using the device, the person desiring to obtain the "page boy" coiffure washes her hair and parts same in the desired manner. The apparatus is then placed on said person's head with the relatively thick, U-shaped member 12 disposed behind the person's head under the hair, as shown in dotted view in Figure 1, and with the strap member 21 placed over the top portion of the person's head and secured to plate member 15 by engaging a selected aperture 23 with the lug 24 on said plate member 15, in accordance with the size and shape of the person's head. The relatively thin, U-shaped member 18 is elevated and the hair is combed to extend over the relatively thick, U-shaped member 12. The hair being combed as smoothly as possible over member 12. The relatively thin, U-shaped member 18 is then lowered over the hair so that it tends to press the hair inwardly over the relatively thick, U-shaped member 12 at the lower rear portion of the person's head, causing the lower marginal portion of the hair to curl over the relatively thick, U-shaped member 12. The marginal portion of the hair over the member 12 defines a roll, designated at 26. A hair net may then be fastened on the person's head, extending from the top of the person's head and under and around the roll 26, holding the roll 26 in curled relationship around the thick, U-shaped member 12. When the hair is dry, the hair net and the apparatus may be removed, leaving the hair shaped and formed to the desired "page boy" coiffure.

It will be understood that when it is desired to trim the marginal portion of the hair, the U-shaped member 12 may be employed as a guide, the points of the scissors being inserted

in the groove 13 and moved along the hair to trim the same, whereby means is provided for trimming the hair to provide a smooth and neat hair margin, said margin extending around the back of the head.

While a specific embodiment of an improved hair-setting appliance has been disclosed in the foregoing description, it will be understood that various modifications within the spirit of the invention may occur to those skilled in the art. Therefore, it is intended that no limitations be placed on the invention except as defined by the scope of the appended claims.

What is claimed is:

1. A hair-setting appliance comprising a relatively thick, generally U-shaped bar member, said bar member being rounded in cross-section and being adapted to be engaged back of the user's head, a strap member secured to one end of said bar member and arranged to lockingly engage the other end of said bar member, said strap member being adapted to be engaged over the top of the user's head, and an auxiliary, relatively thin U-shaped member pivotally connected at its ends to the ends of the thick U-shaped member and adapted to engage over the user's hair adjacent the back of the user's head opposite the thick U-shaped member said U-shaped member being formed with an outwardly facing groove extending the major portion of the length of the U-shaped member for guiding a scissors along the user's hair.

2. A hair-setting appliance comprising a relatively thick, generally U-shaped bar member of

substantially circular cross section adapted to be engaged back of the user's head, respective plate members pivotally connected to the ends of said U-shaped bar member, a strap member secured at one end thereof to one of said plate members, a projection on the other plate member, said strap member being formed with longitudinally spaced openings adjacent its other end adapted to be selectively engaged with said projection, said strap member being adapted to be engaged over the top of the user's head, and an auxiliary, relatively thin U-shaped member pivotally connected at its ends to the plate members and adapted to engage over the user's hair adjacent the back of the user's head opposite the thick U-shaped member said thick U-shaped member being formed with an outwardly facing groove extending for the major portion of the length of the U-shaped member, for guiding a scissors in trimming the hair at the back of the user's head.
